UNITED STATES PATENT OFFICE.

GEORGE E. MARKS, OF NEW YORK, N. Y., ASSIGNOR TO THE FIRM OF A. A. MARKS, OF NEW YORK, N. Y.

ARTIFICIAL LEG.

1,032,074.

specification of Letters Patent.

Patented July 9, 1912.

Application filed March 22, 1912. Serial No. 685,432.

To all whom it may concern:

Be it known that I, GEORGE E. MARKS, a citizen of the United States, and a resident of New York city, in the county of 5 New York and State of New York, have invented certain new and useful Improvements in Artificial Legs, of which the following is a specification.

The invention relates to improvements in 10 artificial legs, and consists in the novel features and structure hereinafter described, and particularly pointed out in the claims.

One object of the invention is to provide a leg having a socket which admits of lateral 15 adjustment to meet the varying conditions of the stump of the wearer, and another object of the invention is to provide an especially durable construction with respect to the lower leg part and foot of the socket and 20 one capable of resisting the influence of water, the socket of my invention enabling the wearer to walk in water or wet places without the socket becoming prejudicially affected thereby.

25 In carrying out my invention I provide a socket having a foot member secured thereto and an upper leather member adapted to be secured upon the leg of the wearer above the knee and connected with the socket by 30 special side hinge parts and rear lacings, said socket being vertically bifurcated front and back and provided with leather lacers or auxiliary socket-members and lacings therefor at the front and back by which the 35 sides of the socket may be drawn toward each other or permitted to separate according to the requirements of the stump as the same from time to time changes. The hinge parts connecting the sides of the bifurcated

40 socket with the upper leg member constitute side knee joints which are of special construction admitting of the lateral adjustment of the sides of the socket, each of said parts comprising two hinges arranged 45 at right angles to each other and permitting movement sidewise as well as front and back. Sockets of artificial legs have heretofore been adjustable from front to back but this character of adjustment is objectionable 50 since it results in undue pressure on the tibia and popliteal area, with the resultant consequences.

The foot member of the leg comprises a core, a rubber foot inclosing said core and

extending above the joint between the same 55 and the socket-member of the leg and means securing the said core to said socket-member and comprising, among other features, a metal sheath at the back and sides permanently riveted to the socket of the leg and 60 said core and preferably being of aluminum, duralumin, copper or other material not susceptible to the corroding influence of moisture.

The invention will be fully understood 65 from the detailed description hereinafter presented, reference being had to the accompanying drawings, in which:

Figure 1 is a front elevation of an artificial leg constructed in accordance with and 70 embodying my invention; Fig. 2 is a side elevation, partly in central vertical section, of the same; Fig. 3 is a rear elevation of the same; Fig. 4 is an elevation of a detached portion of the side of the socket, with the 75 covering leather removed to more fully disclose the hinge-member secured thereto; Fig. 5 is a vertical section through the upper portion of the socket on the dotted line 5—5 of Fig. 2, and Fig. 6 is a horizontal 80 section through the socket on the dotted line 6—6 of Fig. 1.

In the drawings, 10 designates the socket having a foot member 11 and connected by side hinge-members with an upper leather 85 securing member 12, said hinge-members being at the knee-joint and said member 12 being adapted to be secured by lacing upon the leg above the knee.

The socket 10 may be constructed of wood, 90 aluminum or other suitable material and it is bifurcated front and back from its upper end downwardly to within a reasonable distance from the foot, whereby the upper portion of said socket becomes comprised of 95 two side portions 13, 14 adapted to be drawn laterally toward or allowed to recede from each other in accordance with the adjustment desired in adapting the socket to the stump it is to receive. The socket 10 above 100 the foot member 11 will preferably be in one integral piece of material, the front and back slots 15 therein and the thickness of the walls of the socket being proportioned to allow sufficient resilience in the sides of 105 the socket to permit of the lateral adjustment of the same toward and from each other.

The socket 10 is provided with a soft leather lining 16 of tubular formation which extends upwardly over the upper edges of the socket and is not of unusual character.

5 Upon the upper side section of the socket are secured strong leather laces or auxiliary socket-members 17, 18 having along their vertical edges, which are adjacent to the outer edges of the slots 15, means by which 10 said members may be drawn toward each other, front and back, to effect the proper lateral adjustment of the sides of the socket, the means shown for drawing the members toward or permitting them to recede from 15 each other being leather lacings 19 threaded through eyelets in the adjacent edges of said members. The socket-members 17, 18 are rigid with the socket 10, but since they are separated front and back in line with the 20 vertical slots 15 in the sockets, said socket-members may be readily utilized as convenient means for effecting the correct lateral adjustment and set of the sides 13, 14. The members 17, 18 are secured to the socket 10 25 by means of rivets 20.

The upper leather member 12 is adapted to pass around the leg above the knee and be firmly secured by means of a lacing 21 of usual character. The member 12 is flexibly connected with the back of the socket 30 by means of narrow straps or lacings 22, some of which connect with the back of the side portion 13 and others with the back of the side portion 14 of said socket, as shown 35 in Figs. 1 and 3.

The sides of the socket are connected with the sides of the securing member 12 by hinge-parts comprising, at each side of the leg, a lower bar 23 secured to the socket 40 (Fig. 4), an upper bar 24 secured to the member 12 and an intermediate bar 25 which is bifurcated from front to back at its upper part and receives between its sides the lower end of the bar 24, the latter being hingedly held between the said sides 45 on a pintle-screw 26 extending transversely of the leg. The lower end of the bar 25 is secured on a rivet or pintle 27 between vertical ears 28 formed on the upper end of the bar 23, said rivet or pintle 27 extending 50 from front to back through the engaging portions of the bars 25, 23 and serving to permit of a lateral hinged motion of the bar 25 or a lateral hinged motion of the bar 55 23 during the lateral adjustment of the socket. The screw-pintles 26 constitute the axes of motion at the knee-joint during the use of the leg, and the presence of the hinges connecting the bars 25 with the bars 60 23 below said pintles 26 and at right angles thereto, enables the sides of the socket to be drawn closer together or permitted to expand outwardly in a direction from each other without the centers of motion represented by the pintles 26 being distorted 65

or thrown out of their proper axis. The hinge-members represented by the bars 23, 24, 25 correspond with each other, and the bars 23 for the greater portion of their length are concealed by the leather socket-members 17, 18, while the bars 24 are concealed throughout their upper portions by leather coverings 29 secured to the opposite sides of the member 12 by sewing or otherwise. 75

The foot-member 11 comprises a core 30 and a rubber or like covering 31, and said core is secured to the lower end of the socket 10 by dowel pins or the like 32, and especially by means of a metal sheath 33, 80 which extends across the joint between the socket and core and incloses a portion of the back and sides of said socket and core, said sheath being riveted to the socket and core and serving very greatly to strengthen 85 the connection between said parts and render it possible for the wearer of the leg to walk in wet places without prejudicially affecting the leg. I regard the addition of the metal sheath 33 as of considerable 90 importance in respect to the durability and desirability of the leg. The sheath 33 will be of durable character and may be made of aluminum, duralumin, copper or other metal not readily susceptible to the 95 corroding influence of moisture.

I have sought in the production of the leg as a whole to provide a leg possessing great durability throughout and one adapted to be adjusted to suit the varying conditions 100 of stumps and legs, one object being to provide a socket which may be made comfortable to the wearer under the varying changes that may take place in his stump. Stumps that are large and flabby are likely to 105 change in size when put under pressure, as they are when wearing artificial limbs. There are also stumps of older amputations that change from time to time. One of the especially desirable features of my invention is that I provide for lateral adjustment 110 of the sides of the socket, instead of reducing the socket from front to back, whereby in the adjustment and use of my socket there is an absence of increased pressure on the shinbone and on the blood vessels back of the knee and comfort to the wearer is secured. 115

What I claim as my invention and desire to secure by Letters Patent, is:

1. An artificial leg comprising a socket-member having sides capable of lateral adjustment and means for effecting such adjustment, an upper member to be secured on the leg of the wearer above the knee, and hinge-members connecting said socket and upper member and comprising, at each side of the leg, two hinges at right angles to each other, one being transverse on the axis of motion of the leg during the use thereof 130

and the other extending from front to back to admit of the lateral adjustment of the sides of the socket.

2. An artificial leg comprising a socket-member to receive the stump, a foot-member comprising a core covered with rubber, and means securing said core to said socket-member comprising, with other securing features, a metal sheath inclosing and se-

cured to the back and sides of the adjacent 10 portions of said socket-member and core.

Signed at New York city, in the county of New York and State of New York, this 20th day of March A. D. 1912.

GEORGE E. MARKS.
